UNITED STATES PATENT OFFICE.

CHESTER COMSTOCK, OF NEW YORK, N. Y., AND JACOB B. CONOVER, OF METUCHEN, NEW JERSEY.

MILK-CAN.

SPECIFICATION forming part of Letters Patent No. 650,967, dated June 5, 1900.

Application filed February 26, 1900. Serial No. 6,478. (No model.)

To all whom it may concern:

Be it known that we, CHESTER COMSTOCK, residing at New York, (Brooklyn,) in the county of Kings and State of New York, and 5 JACOB B. CONOVER, residing at Metuchen, in the county of Middlesex and State of New Jersey, citizens of the United States, have invented certain new and useful Improvements in Milk-Cans, of which the following is a specification.

This invention relates to milk-cans, and more particularly to the construction of the neck thereof; and it has for one object the provision of an improved can provided with 15 a reinforced neck comprising a pair of neck portions, one integral with the breast and the other integral with the bowl, overlapping each other throughout the entire width or height thereof, one of said neck portions being provided with an integral flaring locking-flange, chamfered or beveled so that its free edge will form at one side of such neck substantially a flush connection or joint with the member with which it engages, thereby to do 25 away with the provision of a recess formed in the metal or by bending the metal for the reception of such flange.

A further object of the invention is to furnish a milk-can formed of a breast member 30 provided with a rigid or integral neck and a bowl member having a rigid or integral neck, one of said necks extending within and being overlapped by the other neck and one of said necks having a reinforcing and locking flange 35 extending at an angle to the plane of said neck and in engagement with an un recessed face of one of said members.

In the drawings accompanying and forming part of this specification, Figure 1 represents the upper part of a milk-can, partially in section, showing the present improvement. Fig. 2 is a similar view to Fig. 1, showing a reversal of the construction presented in said Fig. 1. Fig. 3 is a sectional view substantially similar to the part shown in section in Fig. 2, but showing the bowl and breast disconnected; and Fig. 4 is an enlarged sectional view of the neck portion illustrated in Fig. 2.

Like characters denote similar parts in all 45 the views.

For the purpose of more clearly illustrating

the differences in construction between the present improvement and the prior art it is deemed necessary to herein briefly refer to such prior art.

We are aware that it is not new to form the bowl, neck, breast, and a portion of the body in one piece or as an integral structure, which, however, aside from the difficulty in the manufacture of such a structure, results 55 simply in the production of a can which must necessarily be weak at the neck portion, where it should be of great strength and rigidity, since such neck, being formed in one piece with the bowl and breast, must be bent at 60 two points, to the injury of the fibers of the metal. Moreover, since the neck is of the same thickness as the breast and bowl it is therefore not reinforced at that point where it is subjected to rough usage in the handling 65 of the can, it being the practice to catch the same, especially when empty, under the flaring mouth, so that cans made in this manner frequently become bent at the neck thereof, such flexure materially interfering with the 70 proper fitting of the cover, whereby the usefulness of the can is impaired. We are also aware that it is not new to provide a bowl and a breast each with an integral neck; but in this construction no means is provided 75 other than the tinning material for maintaining the bowl and breast together. We are also aware that it is not new to provide the bowl with an integral neck and the breast with an integral neck overlapping the bowl-neck and having a part adapted to overlap 80 the breast and thereby provide not only a reinforced neck, but a reinforced breast. We are also aware that it is old to provide a bowl and a breast formed independently of 85 each other and connected together by a pair of necks formed independently of such bowl and breast and each provided with flaring flanges overlapping the bowl and the breast. In this construction, however, the necks are 90 not formed integral with the bowl and breast, but are separate therefrom, while the edges of the flaring flanges form a plurality of relatively-large joints, which easily become impregnated with foul milk and germs. We 95 are also aware that it is old to provide the bowl with an integral neck and the breast 100

with an integral neck and a flaring locking-flange, the bowl or breast being recessed adjacent to its juncture with its neck for the reception of said locking-flange, thereby to 5 form a flush joint. In this construction a flush joint is provided to prevent the fouling of the can; but to provide such flush joint it is necessary that an annular recess be formed in the bowl or breast or that such bowl or 10 breast, as the case may be, be bent to form said recess. In either event the formation of this recess tends to weaken the can, since if the recess be formed in the metal some of the metal must necessarily be removed, while if 15 the metal be bent such flexure strains the fibers of the metal, so that weakness results at a point where the can should be of considerable strength and where it has already been bent—namely, at the juncture of the bowl and 20 the neck or of the breast with the neck, as the case may be—so that in such construction by reinforcing the neck one part of the neck is robbed of its strength and resisting qualities to reinforce another part thereof.

25 The above is, so far as we are aware, the only construction in which a flush joint is provided, and as it is a well-known fact that a few drops of foul milk will when brought into contact with pure milk during even a 30 short railroad journey foul the entire contents, consisting of many gallons, it will be readily seen that the provision of a flange the edge of which is not substantially flush with the part with which it engages merely 35 leaves a joint of considerable size to constitute a means of retaining foul particles of milk, so that it is absolutely necessary if a flange be provided for locking the bowl and breast together and which is essential to a 40 rigid and durable structure that such flange shall constitute a flush joint to all intents and purposes with the part with which it engages; and to do this without weakening the metal adjacent to the juncture of the neck by the 45 bending thereof or the formation of a recess therein, while at the same time to provide an organization in which the bowl will have an integral neck and the breast an integral neck, each formed independently of the other, there- 50 by facilitating the manufacture of the product and forming when assembled a reinforced duplex neck, is the object of the present invention.

To this end the improvement comprises in 55 a general way a bowl having a rigid or integral neck and a breast having a rigid or integral neck, each formed separately from the other and one of said necks having a flaring locking-flange beveled or chamfered toward 60 its free edge and adapted to engage the bowl or the breast, as the case may be, and form therewith at such free edge substantially a flush joint.

In the form thereof herein shown and de- 65 scribed the improvement comprises a bowl 2, the upper edge 3 of which may be reinforced

in any desired manner and having an integral depending neck extending at an angle to such bowl, a breast 5, which may be united to the body in any desired manner, having 70 an upwardly-projecting neck 6 extending at an angle to such breast, the neck of one member adapted to overlap the neck of the other member throughout the entire width or height of such necks. One of these necks—as, for 75 instance, the neck of the breast (see Fig. 2)—is provided with a flaring locking-flange 7, which is beveled or chamfered toward its free edge, so that such edge may be brought into very close engagement with the inner face of the 80 bowl, whereby a flush joint is provided for all practicable purposes, the construction being such that the bowl has a relatively smooth and unbroken inner face from the juncture of the locking-flange with its neck to the upper edge of such bowl.

In another form thereof (shown in Fig. 1) the construction shown in Fig. 2 is reversed, the neck 4 of the bowl 2 having the flaring locking-flange 7', constructed in the manner 90 above specified, whereby it will form with the inner face of the breast substantially a flush joint.

By turning the locking-flange 7 or 7' outwardly at a relatively-sharp angle to its neck 95 it is effective to lock the parts firmly together, and by providing such flange with a beveled or chamfered edge the upper surface 7" of such flange merges into the inner surface 8 of the bowl or breast, as the case may be, without the formation of any appreciable joint.

By the provision of a can having the construction set forth it will be seen that the bowl and the breast may be formed separately from each other, which is an essential feature 105 in the manufacture of milk-cans, while at the same time a reinforced neck is provided consisting of two parts of the same width or height, each of substantially the same thickness as the metal of the bowl or breast and 110 united by a locking-flange so formed that substantially a flush joint is provided without the necessity of bending the metal of the bowl or breast to form a recess, thereby straining the fibers of the metal, or to remove a portion 115 of such metal to form such recess.

When the parts have been assembled and firmly located together, they are subjected to the usual tinning operation, whereby the 120 seams are filled and the parts firmly united by the tinning material, which acts as a soldering medium. In practice this tinning material will constitute a bridge between the practically inappreciable edge of the beveled flange and the face of the bowl, thereby positively preventing the formation of any appreciable joint for the retention of foul particles of milk or germs.

From the foregoing it will be seen that in the present improvement a can is secured 125 which from a sanitary point of view is equal in every way to a can made without joints,

while at the same time it is of greater durability and rigidity and more easily constructed than such jointless can, while no part of the bowl or breast is weakened by the formation of a recess or the flexing or bending of the metal to provide for the reception of the locking-flange.

Having described our invention, we claim—

1. A milk-can having a breast member provided with a rigid or integral neck, and a bowl member provided with a rigid or integral neck, one of said necks extending within and being overlapped by the other neck, and one of said necks having a beveled or chamfered locking-flange extending at an angle to the plane of said neck and in engagement with and merging into the inner surface of one of said members.

2. A milk-can having a breast member provided with an integral neck, and a bowl member having an integral neck, one of said necks extending within and being overlapped by the other neck throughout its entire width or height, and one of said necks having a reinforcing and locking flange extending at an angle to the plane of said neck and in engagement with an un recessed face of one of said members.

3. A milk-can having a bowl provided with a depending rigid or integral straight neck, and a breast having an upwardly-extending rigid or integral straight neck located inside of and overlapped by said bowl-neck throughout its entire width or height, said breast-neck having a locking-flange bent at an angle

thereto and in engagement with an un recessed face of said bowl.

4. A milk-can having a bowl provided with a depending rigid or integral neck, a breast having an upwardly-extending rigid or integral neck projecting interiorly of and overlapped throughout its entire width or height by said bowl-neck, and having a chamfered or beveled locking-flange extending at an angle to the plane of said neck and in engagement with and merging into the inner face of said bowl to form substantially a flush joint without the flexure of the metal of said bowl or the provision of a recess therein for the reception of said flange.

5. A milk-can having a breast member provided with a rigid or integral straight neck, and a bowl member provided with a rigid or integral straight neck, one of said necks extending within and being overlapped by the other neck, and one of said straight necks having a beveled or chamfered locking-flange extending at an angle to the plane of said neck and in engagement with, and merging into the inner face of, one of said members, thereby to form substantially a flush joint without the flexure of the metal of such member or the provision of a recess therein for the reception of said flange.
